UNITED STATES PATENT OFFICE.

ANDREW J. CULBERTSON, OF SAN ANDREAS, CALIFORNIA.

TACK.

SPECIFICATION forming part of Letters Patent No. 257,213, dated May 2, 1882.

Application filed September 27, 1881. (No model.)

To all whom it may concern:

Be it known that I, ANDREW J. CULBERTSON, of San Andreas, county of Calaveras, State of California, have invented an Improved Harness Tack or Rivet; and I do hereby declare the following to be a full, clear, and exact description thereof.

My invention relates to an improvement in tacks for securing the layers of leather or other material together, as will be more fully described by reference to the accompanying drawings, in which—

Figure 1 is a view of my tack or rivet. Fig. 2 shows it as turned over to rivet two pieces of leather together. Fig. 3 is a view of a strap, showing the manner of fastening with my tack. Fig. 4 shows the form of tack now in use as applied to the leather.

My tack A is made of copper or other malleable metal; and it consists of a round and nearly straight body, with a bar-head resembling a letter T, and it has a tapered and slightly-flattened point, so that when driven through the leather and into contact with a piece of iron upon the reverse side this point will be turned back and enter the leather from that side so as to clinch or rivet it firmly. This tack is especially useful in securing the parts of harness together and in the formation of long heavy loops, the work being done more quickly than by sewing, and it will not rip.

To use the tack I take the thickness of leather to be riveted, and use tacks one-eighth of an inch longer than this thickness. If desired, the leather may be channeled to receive the heads of the tacks, or the tacks may be driven down so that the heads sink into the

surface of the leather; but when channeled the leather may be closed over the tack-heads and form a neat finish. The leather is laid upon a piece of iron, so that when driven the points of the tacks will be reversed and clinched into the leather. A seam formed in this manner presents a nearly continuous line or thread of metal to bind the parts together, formed by the heads of the tacks lying in line, and is much stronger than when formed of thread, which is liable to rot and rip, and if exposed will become worn and cut through. Flat V-shaped tacks form too long holes, which are apt to crack so as to unite and form a long cut in the line of the seam, which my tack will not do.

I am aware that flat V-shaped tacks have been formed by special machinery having flat elongated heads joined together in a continuous strip; and I do not claim such tacks. They cannot be used for a continuous seam, because they are so much wider at the head than at point that when driven in they will force the leather into a curve, as shown in Fig. 4.

What I do claim as new, and desire to secure by Letters Patent, is—

An improved harness-tack formed of malleable metal, having a T-shaped head, a body having straight parallel sides, and a flattened point.

In witness whereof I have hereunto set my hand.

ANDREW JACKSON CULBERTSON.
